UNITED STATES PATENT OFFICE.

JOHN LA RUE ROBINSON, OF RENO, NEVADA.

DESIGN FOR AN AMPUL.

58,687.

Specification for Design.

Patented Aug. 9, 1921.

Application filed October 13, 1920. Serial No. 416,763. Term of patent 14 years.

To all whom it may concern:

Be it known that I, JOHN LA RUE ROBINSON, a citizen of the United States, residing at Reno, in the county of Washoe and State of Nevada, have invented a new, original, and ornamental Design for an Ampul, of which the following is a specification, reference being had to the accompanying drawing, forming part thereof.

Figure 1 is a side elevation showing my new design,

Fig. 2 is a top plan view, showing my new design, and

Fig. 3 is a bottom plan view, showing my new design.

I claim:

The ornamental design for an ampul as shown.

J. LA RUE ROBINSON.
